UNITED STATES PATENT OFFICE.

AUGUST F. OSTERLIND AND GOTFRID S. ELMQUIST, OF ST. PAUL, MINNESOTA.

PRINTER'S CHASE-RACK.

1,025,296.

Specification of Letters Patent.

Patented May 7, 1912.

Application filed January 4, 1911. Serial No. 600,708.

To all whom it may concern:

Be it known that we, AUGUST F. OSTERLIND and GOTFRID S. ELMQUIST, citizens of the United States, residing at St. Paul, in 5 the county of Ramsey and State of Minnesota, have invented a new and useful Improvement in Printers' Chase-Racks, of which the following is a specification.

Our invention relates to improvements in 10 racks for printers' chases and its object is to provide a rack into which the chases will slide easily, accommodating chases of different sizes and keeping them in an upright position and separated for use. Our device 15 accomplishes these objects in a compact rigid frame with two tiers of racks accessible on each side.

In the drawings with which we have 20 illustrated our device and which form a part of the specification, Figure 1 is a perspective of our device with chases in position, and Fig. 2 is an end elevation of the rack.

In these drawings is shown a rack A made up of bottom frame B and top frame 25 C spaced apart by posts. The frames are rectangular, the frame B being wider than the frame C, and made up of side pieces 2 and end pieces 3 with a cross piece 4. On the end pieces 3 and cross piece 4 stand the posts 5, 6 and 7, carrying the top frame C which is made up of sides 8 and ends 9. The posts 6 and 7 on the center line of the rack rise above the top frame C and support a longitudinal bar 10 to the sides of which 35 are bolted angle bar spacers 11, which have notches 12 cut in the outstanding leg of the angle. Midway between the top and bottom frames the posts 6 and 7 carry longitudinal bars 13 with spacers 14 similar to spacers 40 11. The side pieces 8 of the frame C support grooved slides 15 which extend transversely across the frame and correspond in position with the notches 12 in the spacers. The grooves 16 of the slides 15 are designed 45 to receive the edge of a printer's chase 17 resting in the slides and supported in the notches 12 of the spacers. Similar slides 18 are carried by the frame B and correspond with the notches 12 in the spacers 14. The 50 slides 15 and notches 12 are so spaced apart as to give free access to the chases resting in them.

The position of the spacers 11 and 14 above the slides 15 and 18 is such as to support the chases on edge in the slides, the

frame C being fitted to the smaller chases and the frame B to the larger chases. The spacers 11 and 14 on either side of the longitudinal bars 10 and 13 at the center of the rack, provide support for chases on both 60 sides of the rack as shown in the drawings. The rack is stiffened laterally by braces 19 between posts 6 and the end pieces 3.

In accordance with the patent statutes we have described the principles of operation of 65 our invention together with the apparatus which we now consider to represent the best embodiment thereof but we desire to have it understood that the construction shown is only illustrative and that the invention can 70 be carried out by other means and applied to uses other than those above set forth within the scope of the following claims.

Having described our invention, what we 75 claim as new and desire to protect by Letters Patent is:—

1. A printer's chase rack, comprising in combination, a supporting frame, a series of channel irons disposed on said frame in substantially parallel position and having 80 their concave sides upward to receive the edge of a chase sliding therein, and a spacing bar mounted on said frame midway of the length of said channel irons and adapted to receive and engage the forward edges of 85 chases slid into said channels, whereby chases may be supported in substantially vertical position on each side of said spacing bar in each of said channels.

2. In a printer's chase rack, a supporting 90 frame, a series of channel irons disposed on said frame in substantially parallel horizontal position each of said irons having its concave side upward to receive the edge of a chase slid therein, and a spacing bar 95 mounted on said frame above said channel irons and spaced away from the ends thereof, having notches directly above said channel irons adapted to receive the ends of plates slid into the concavities of said channel irons and co-operating therewith to maintain said chases in vertical position.

In testimony whereof, we have signed our names to this specification, in the presence of two subscribing witnesses.

AUGUST F. OSTERLIND,
GOTFRID S. ELMQUIST.
